UNITED STATES PATENT OFFICE.

GEORGE W. OAKES, OF CRYSTAL CITY, MISSOURI, ASSIGNOR TO PITTSBURGH PLATE GLASS COMPANY, A CORPORATION OF PENNSYLVANIA.

PLATE-GLASS INSPECTION CLAMP.

Application filed April 18, 1922. Serial No. 555,379.

To all whom it may concern:

Be it known that I, GEORGE W. OAKES, a citizen of the United States, and a resident of Crystal City, in the county of Jefferson 5 and State of Missouri, have made a new and useful invention in Improvements in Plate-Glass Inspection Clamps, of which the following is a specification.

The invention relates to clamps for use in 10 examining or inspecting plate glass. In inspecting such glass, the sheets are placed in vertical position so as to get a proper application of light thereto and carefully examined for the location of defects and to determine the grades. The present invention is 15 designed to provide a simple means which is easily operated for holding the sheets securely in upright position during the process of examination. One embodiment of the invention is illustrated in the accompanying drawings wherein:

Figure 1 is a front elevation of the clamp in position of use engaging one edge of a sheet of glass. Fig. 2 is an edge elevation. 20 Figs. 3 to 7 are detailed views of parts of the clamp and Fig. 8 is a transverse section through one of the clamping members on the clamping frame.

Figs. 1 and 2 illustrate only one of the 25 clamps which are employed in holding a sheet of glass A in vertical position for inspection purposes, the other clamp being located at the other end of the sheet and being the same in construction as the one shown in 30 Figs. 1 and 2. The clamp is pivotally mounted on the post 1, and comprises a vertical angle 2 and three engaging members 3, 4 and 5 which are riveted to the angle 2 and which are adapted to engage the edge of the 35 sheet when the clamp is in the position of Fig. 1. These members 3, 4 and 5 are provided on their faces next to the glass with felt pads 6 to yieldingly engage the glass.

The angle frame member 2 has one flange 40 at each end bent in as indicated at 7 (Fig. 4), which ends are perforated and adapted to receive the pivot rod 8. The post 1 carries a pair of eye bolts 9, which are screwed into the post above and below the ends of 45 the frame member 2 with their eyes in alignment with the perforations in the flange at 7, so that when the rod 8 is inserted through the eye bolts and the ends of the angle 2, a 50 pivotal support is provided.

55 Projecting beneath the lower end of the

clamp and secured to the post is the catch 10 shown in detail in Fig. 6, such catch being provided with the inclined surface 11. The lower clamping member 5 carries the latch 12 pivoted at 13 and provided with an end 14 for engaging a stop pin 15 on the member 5 when the latch reaches the position indicated in Fig. 2. The latch is also provided with an engaging part 16 adapted to engage the surface 11 on the catch 10 when the latch is swung to locking position. This portion 16, in its movement to locking position first engages the surface 11 at its upper end, and as the latch moves down a camming effect is secured, causing the clamp to swing around its pivot 8 so that the felt covered faces of the members 3, 4 and 5 yieldingly engage the glass, pressing it against the post. When the latch reaches the position of Fig. 2, it is in full locking 75 position and the relation of the pivot 13 to the surface 11 is such that the latch will maintain itself in this position. In order to release the clamp, the latch is swung upward from the position of Fig. 2, thus freeing it from the catch 10, after which the frame can be swung around its pivot and out of the way of the glass so that the plate may be removed and another one substituted.

What I claim is:

1. In combination in a glass supporting device, a vertical post adapted to engage a sheet of glass to be examined along one of its vertical edges, a clamping frame hinged to the post and adapted to swing to holding position over said edge, and cooperating cam clamping means on the post and frame for causing the frame to press upon the glass and for securing the frame in such position, said clamping means being arranged to positively lock the clamping frame in operative position.

2. In combination in a glass supporting device, a vertical post adapted to engage a sheet of glass to be examined along one of its vertical edges, a clamping frame hinged to the post and adapted to swing to holding position over said edge, a catch member secured to the post beneath the frame and a pivoted latch carried at the lower end of the frame and adapted to engage the catch when the frame is in holding position.

3. In combination in a glass supporting device, a vertical post adapted to engage a

sheet of glass to be examined along one of its vertical edges, a clamping frame hinged to the post and adapted to swing to holding position over said edge, a catch member secured to the post beneath the frame having an inclined locking surface, and a latch pivoted to the lower end of the frame for movement transversely of the catch and adapted

to engage said locking surface, so that the frame is cammed inward against the glass 10 when the latch is swung to locking position.

In testimony whereof, I have hereunto subscribed my name this 1st day of April, 1922.

GEORGE W. OAKES.
